UNITED STATES PATENT OFFICE

153,903

DESIGN FOR A CAPPING MACHINE GUARD

Manuel S. Resina, Brooklyn, N. Y.

Application October 31, 1946, Serial No. 134,403

Term of patent 3½ years

(Cl. D55—1)

To all whom it may concern:

Be it known that I, Manuel S. Resina, a citizen of the United States of America, residing in the Borough of Brooklyn, city of New York, county of Kings, and State of New York, have invented a new, original, and ornamental Design for a Capping Machine Guard, of which the following is a specification, reference being had to the accompanying drawing, forming part thereof.

Figure 1 is a front perspective view of a capping machine guard, showing my new design.

Figure 2 is a rear perspective view of the capping machine guard of Figure 1.

Figure 3 is a top plan view.

Figure 4 is a bottom plan view of Figure 3.

Figure 5 is a front elevational view.

I claim:

The ornamental design for a capping machine guard, as shown.

MANUEL S. RESINA.
